[57] ABSTRACT

Changes in the support forces on a structural member when it is touched are used to compute the location of the point at which the structural member is touched.

ROUTINE TO MEASURE FORCES BY CAPACITANCE CHARGING TIMEFig. 9

ROUTINE TO COMPUTE LONG-TERM (SLOW) AVERAGES
AND SHORT-TERM (FAST) AVERAGES OF EACH OF THE MEASURED FORCES

Fig. 10

ROUTINE TO COMPUTE X-Y LOCATION OF POINT OF APPLICATION
OF FORCE ON TOUCHPLATE

Enter with SLOW AVERAGES SBL,SBR,STL & STR of measured differential forces for bottom left,bottom right,top left and top right quadrants,respectively, and with corresponding FAST AVERAGES FBL,FBR,FTL & FTR.

Fig. 11

SUBROUTINE TO CALCULATE LOCATION OF APPLIED FORCE

CALL WITH: $R2 = \sum$ LEFT OR BOTTOM DIFFERENTIAL FORCES
 $R3 = \sum$ RIGHT OR TOP DIFFERENTIAL FORCES
 RETURN WITH: $R5 = x$ OR y LOCATION OF FORCE AS BINARY FRACTION
